ROTARY CARD FILING DEVICE

Emil E. Knittel, Malverne, N. Y.

Application February 1, 1947, Serial No. 725,949

5 Claims. (Cl. 45—3)

1

This invention relates to devices for filing cards and the like and more particularly to rotary filing devices.

As I pointed out in my application Serial No. 564,563 filed November 22, 1944, now Patent Number 2,418,357, it is not uncommon practice in many types of businesses to have a filing system wherein information, data or records are kept on individual cards. The cards may be used for various purposes and it is customary to keep them in a systematic manner in files where they may be referred to conveniently. In some systems it is necessary to remove and replace the cards from time to time for one purpose or another.

In that application I showed a filing cabinet having a rotary drum which is provided with an annular recess in which to insert cards to be filed and I disclosed therein the use of an endless belt having one of its runs adjacent the underside of the drum to prevent the cards in the recess from falling out when the drum is rotated. Since filing that application I have made improvements upon my original disclosure, the features of which are advantageous in the construction of certain types of filing cabinets which embody an endless belt.

The embodiments disclosed herein utilize the principle of an endless belt to prevent cards from falling away from the drum, which principle is disclosed in my above-mentioned application but the arrangement of the upper run or runs of the endless belt or belts may be modified. In addition I have provided a very simple yet most effective arrangement for mounting the bearings which support the drum axle for rotation which at the same time provides for strengthening the side walls of the cabinet enclosing the drum. Also included is the provision of an attractive yet light hand ring for the card filing drum which has been found to be desirable in some types now in commercial production.

Although the novel features which are believed to be characteristic of this invention will be pointed out in the claims appended hereto, its objects and advantages, and the manner in which it may be carried out, may be better understood by reference to the following description taken in connection with the accompanying drawings forming a part hereof, in which

Fig. 1 is a side view in elevation partly broken away to expose a cross-section of a filing cabinet in accordance with my invention showing a single belt arrangement and, among other things, the means for mounting the drum axle bearings;

Fig. 2 is a view taken on line 2—2 of Fig. 1;

2

Fig. 3 is a partial view in cross-section to larger scale showing the hand ring and the way it is secured to a drum side wall disk;

Fig. 4 is a partial view to larger scale showing the shape of the compartment-forming members and the way they are secured to the drum side wall disks;

Fig. 5 is a view in cross-section of a filing cabinet showing the manner of mounting the endless belt or belts so that their upper runs may be positioned above the axis of rotation of the drum, the view being on line 5—5 of Fig. 6; and

Fig. 6 is a plan view of Fig. 5 with the top wall of the enclosure cabinet removed at line 6—6 of Fig. 5.

Referring now more particularly to Figs. 1 to 4, there is shown, a drum 10 having card filing compartments at its periphery. The drum is mounted for rotation within a box-shaped cabinet or housing 11. An endless belt 12 having one of its runs adjacent the compartments is provided to prevent cards mounted on the drum from falling out of the compartments when the compartments are below the axis of the drum.

25 The enclosure cabinet 11 is made of sheet metal, preferably of light weight. It comprises side walls 13 and 14, end walls 15 and 16 having inturned flanges to form base members 17 and 18, and a top wall 19. The top wall is provided with an opening 20 through which the upper part of the drum extends.

The drum, designated generally by reference numeral 10, comprises a side disk 21, a side disk 22 and a cylindrical ring or band 23, it being noted that the diameter of the band 23 is less than the diameter of the side wall disks and when mounted as shown there is provided an annular recess 24. The drum may be so designed that the recess has a width and depth to accommodate any given size of cards. The drum has an axle 25 to which the side disks 21 and 22 are secured. Mounted in the recess and circumferentially spaced about the drum are compartment-forming plates 26. These plates together with the side wall disks 21 and 22 and flat ring 23 form a plurality of card filing compartments 27 at the periphery of the drum 10.

It will be noted that the periphery of side wall disk 21 is outwardly and then inwardly rolled to form a rounded peripheral edge 28. The periphery of side wall disk 22 extends outwardly from the center further than does the periphery of disk 21 and it terminates in an annular radius 29 which serves as a means for securing a hand ring 30. The hand ring 30 is made of an ex-

truded plastic tubing material which may be formed into a ring to register with the periphery of the drum disk. To secure it to the disk an annular groove 31 is milled in the side wall of the ring-shaped tube 30 and the hand ring is fastened by screws 32 to the flat part 29 which registers with the groove 31.

The compartment-forming plates 26 are of a width to set snugly within the recess 24 and they have a height so that the upper edge 33 is about flush with the peripheral edge 28 of disk 21. The height of the plates 26 is such as to accommodate the height of cards to be filed on the drum and the width of the compartments, that is, the width of the recess 24, corresponds to the width of the cards. It is to be particularly noted that the outer edge of each plate has a projection 34 which provides a bearing surface 35 upon which the run 36 of the belt 12 rides. These projections 34 with their bearing surfaces contacting the run 36 of the belt eliminates an undue pressure on the cards 37 in the lower part of the drum as the arrangement is such that the pressure of the belt is against the plates 26 and the cards in the lower compartments may rest on the belt.

The endless belt 12 is trained over ball bearing rollers 40 and 41 mounted in brackets secured to cross pieces 42 and 43 and over similar rollers 44 and 45 mounted in brackets secured to the base members 17 and 18 respectively. The belt is endless and may be of any suitable material but preferably of rubberized composition having some elasticity but which will not be materially affected by temperature or humidity changes. It will be observed that the belt is so arranged that a substantial run is adjacent to and in contact with the plates 26, it being necessary to have a sufficient length of run that the belt lies adjacent to the arc of the drum below its axis so that cards will not fall out of their compartments when the drum is rotated or when the compartments are under the axis of the drum.

The drum 10 is so mounted in the cabinet that a substantial length of arc above its axis extends through the opening 20 in the top wall of the cabinet. Thus cards in the compartments in this upper arc are accessible for removal or replacement or to be otherwise handled. The inner edges of cards 37 in these compartments rest on the band 23. It will be understood from the foregoing that the outer edges of the cards in the compartments below the axis rest on the belt and the cards are thereby retained in their compartments. Consequently, the cards need not be provided with holes, slots or other means for holding them on the drum.

Inasmuch as there is a considerable weight to be carried when the filing drum is provided with a full complement of cards and it is desirable to construct even the larger sizes of cabinets of lightweight sheet metal, I have provided simple yet effective frame members for mounting the bearings which carry the drum axle which in turn carries the weight of the drum. At the same time the side walls of the cabinet are strengthened by the frame members which carry the bearings. The journals 49 at the ends of the drum axle 25 extend into and ride in bearings 50 and 51. These bearings are of the self-lubricating type and have a simple tubular shape. The bearings 50 and 51 are carried on vertical angle iron framing members 52, 52 and 53, 53 secured to the cabinet side walls 14 and 13 respectively. To hold the bearings in place on these angle irons the flanges are pressed out as shown in Fig. 1 to form a cup-

5 shaped cavity 48 to receive and hold the bearing. Thus, for example, flange 54 is pressed out at 55 and flange 56 is pressed out at 57 to conform with the exterior shape of the bearing so that the bearing 51 can be merely pressed into the cavity 48 and it will be retained there. This arrangement provides a very strong, rugged construction.

10 It may be noted also that plates 26 are provided with projections 58, one or more on each side edge. In assembling the drum these projections extend through registering radially disposed apertures 60 in the side wall disks 21 and 22 and are then peened over as shown at 59. This arrangement provides a drum of great strength even though lightweight aluminum sheet metal is used in its construction.

15 The operation of the device will be apparent from the foregoing description. Suffice it to say that the drum will carry more cards for a comparable size of other filing cabinets of the same size because in other types sufficient space must be allowed on the drum to fasten the cards to it and this often requires a distortion of the cards. In my device this drawback is eliminated. When 20 it is desired to move any compartment to the upper part of the cabinet so that the cards in that compartment will be exposed at the opening 20 all that need be done is to rotate the drum. This is facilitated by using the hand ring 30. Those cards which are in the compartments below the axis can not fall out as they ride along on the run 36 of the belt 12 adjacent the compartments, it being understood, of course, that the belt moves along with the rotation of the drum. It may be noted also that the cabinet is mounted on casters 47 so that it may be moved with facility from place to place.

25 To illustrate the feature of an endless belt arrangement wherein one run of the belt is adjacent the periphery of the drum and extending below its axis while the upper run extends across the cabinet above the drum axis, I have chosen to show in Figs. 5 and 6 a cabinet having two endless belts. It will be understood, however, that this arrangement may be adapted to a single belt cabinet.

30 As shown, the cabinet comprises side walls 114 and 115, end walls 116 and 117, and a removable top wall 119. The top wall has an opening 120 through which the top part of drum 110 extends. The end walls have inturned flanges forming base members 117 and 118.

35 The drum 110 comprises two side disks 121 and 122 each alike and similar to disk 21 shown in Fig. 2. A cylindrical band 123 providing an annular recess 124 within which are a plurality of circumferentially spaced compartment-forming members 126 to form a plurality of card compartments 127 around the periphery of the drum.

40 The drum is secured to an axle 125 mounted so that its journals rotate in bearings 151 mounted in cups 148 formed in the flanges of channel irons 154a and 154b, arranged in similar fashion as those shown in Figs. 1 and 2. It is to be noted, however, that the axle 125 extends through side wall 114 to provide a stub shaft 125a to which is secured a hand wheel 130. Thus upon rotation of the hand wheel, the drum rotates.

45 The cabinet is provided with two card retaining endless belts, arranged in parallel spaced relation, trained over the rollers mounted in the cabinet. Each belt is so arranged that a substantial run lies adjacent the card compart-

ments under the drum and the other run returns across the upper part of the cabinet above the drum axis. This arrangement includes a pair of horizontally disposed shafts 200 and 201 mounted to rotate in bearings 203 secured to the side walls 113 and 114 of the cabinet. To shaft 201 are secured a pair of flanged rollers 204 and 205 and to shaft 200 are secured a pair of like rollers 206 and 207. These shafts 200 and 201 are located a short distance below the top wall 119 of the cabinet. Mounted for rotation in brackets 208 secured to the end walls 115 and 116 are two pairs of flanged rollers 209 and 210; and 211 and 212. These rollers are mounted to rotate with their axes vertically disposed. It will be noted that these rollers 209 to 212 are also located a slight distance below the top wall 119 of the cabinet.

An endless belt designated generally by reference character 213 is trained over rollers 204, 206, 209 and 210 and a similar endless belt 214 is trained over rollers 205, 207, 211 and 212. Inasmuch as each of these belts operates in the same way except that one is on one side of the drum and the other on the other side of the drum, it will suffice to describe belt 214. This belt as will be observed in the drawings has a lower run 215 extending under the drum adjacent the compartments, the belt then goes over roller 205 where it twists and then rides over roller 212, the upper run 216 then extends along the length of the cabinet over roller 211 and then twists to go over roller 207. The arrangement of belt 213 is the same on the other side of the cabinet except that it is trained over rollers 204, 206, 209 and 210; the upper run 216a extending across the cabinet above the axis of the drum.

The provision of two belts as shown is very desirable in certain types of larger cabinets. It will be noted also that all the rollers are accessible by merely removing the top plate 119 from the cabinet.

While two belts have been shown in the embodiment of Figs. 5 and 6 it will be understood that a single belt might be used in which case the lower run adjacent the compartments at the lower part of the drum would preferably be centered as shown in Figs. 1 and 2. In this case all that is required is to locate a single flanged roller, such as roller 205, in the center of shaft 201 and a like roller in the center of shaft 200. In this case the pair of rollers 209 and 210 or the pair of rollers 211 and 212 can be dispensed with.

To operate the device shown in Figs. 5 and 6, the drum may be rotated as in the case of the embodiment of Figs. 1 and 2, and the hand wheel 130 may be used to facilitate the movement. Upon rotation of the drum any underside compartments may be brought to the top where the cards therein are readily accessible for removal or replacement or other handling. It will be apparent that cards in the compartments at the lower part of the drum are kept from falling out by the run of the belt lying adjacent these compartments and when the drum is rotated the endless belt or belts, as the case may be, move along with the periphery of the drum. Casters 147 are provided to facilitate moving the cabinet from place to place.

The terms and expressions which have been employed herein are used as terms of description and not of limitation and there is no intention in the use of such terms and expressions of excluding any equivalent of the features shown and described or portions thereof, but it is recognized

that various modifications are possible within the scope of invention claimed.

What is claimed is:

1. A rotary card filing device comprising, a support; a drum mounted on said support for rotation about a substantially horizontal axis, said drum including a pair of lateral flanges providing between them a circumferential annular space adapted to receive file cards; a plurality of substantially radially extending partition members mounted between said flanges for subdividing the said annular space into individual card compartments, said partition members having an upper edge portion protruding above the upper edge of cards in said compartments; an endless belt trained around the lower portion of said drum and engaging said partition members at their protruding edge portions; and means for supporting said belt on said support for freedom to move with said drum when the drum is rotated, said supporting means tensioning the belt to bear against said partition members, said belt tension being sustained by said partition members, cards in said compartments being relieved from the belt tension.

2. A rotary card filing device comprising, a cabinet; a drum mounted in said cabinet for rotation about a substantially horizontal drum axis, said drum having an annular recess about its periphery; an endless belt trained around the lower portion of said drum; a plurality of substantially radially extending partition members circumferentially spaced in said recess for subdividing said recess into a plurality of card compartments adapted to hold file cards, said partition members having an upper edge portion for engaging said belt within said lower portion of the drum and spacing said belt from the bottom of said compartments a distance greater than the height of the cards, whereby the belt tension is sustained by said partition members and the cards in said compartments are relieved from the belt tension.

3. A rotary card filing device comprising, a support; a drum mounted on said support for rotation about a substantially horizontal axis, said drum including a pair of lateral flanges providing between them a circumferential annular space adapted to receive file cards; a plurality of substantially radially extending partitions mounted between said flanges for subdividing the said annular space into a plurality of individual card compartments, said partitions having tab portions projecting above the remainder of the upper edge of the partition; an endless belt trained around the lower portion of said drum and engaging said partition at their respective tab portions; and means for supporting said belt on said support for freedom to move with said drum when the drum is rotated, said supporting means tensioning the belt to bear against said tab portions, the belt tension being sustained by said partitions and cards in said compartments being relieved from the belt tension.

4. A rotary card filing device which comprises an enclosing cabinet having side walls, end walls, and a top wall having an aperture therein; a drum having an annular recess about its periphery; frame members secured to said side walls; bearings supported by said frame members for mounting said drum in said cabinet for turning about a substantially horizontal axis, the top portion of the drum protruding through said apertures; an endless belt trained around the lower portion of said drum; rollers supporting said belt in said

cabinet under tension and with freedom to move with said drum when the drum is rotated; a plurality of substantially radially extending partition members circumferentially spaced in said recess for subdividing said recess into a plurality of card compartments adapted to hold file cards, said partition members having an upper edge portion for engaging said belt within said lower portion of the drum and spacing said belt from the bottom of said compartments a distance 10 greater than the height of the cards, whereby the belt tension is sustained by said partition members and the cards in said compartments are relieved from the belt tension.

5. A rotary card filing device as set forth in claim 4 in which the endless belt is trained over

said drum and said rollers to have an upper and a lower run, the lower run extending around a portion of the drum below its axis, engaging said partitions, the upper run extending above the drum axis and to one side of the drum.
